his ATTORNEY.

UNITED STATES PATENT OFFICE

2,163,811

EXTENSIBLE FASTENER

Arthur R. Richtmyer, Larchmont, N. Y., assignor
to Francis John Bayliss, Walsall, Staffordshire, England

Application September 2, 1938, Serial No. 228,129

3 Claims. (Cl. 241—8)

This invention relates to improvements in extensible fastening means for belts, supporters and other articles of clothing and has for its object to provide an extensible fitting contained partly within the looped end of a belt or the like and partly outside the latter for the purpose of being engaged with the opposite end of the belt or other supporting element and allowing the same to yieldably adjust itself to the wearer.

Heretofore, the extensible fastening means has been mounted wholly within the looped end of the belt and engaged with a buckle or other attachment, which projects outwardly from the sides of the loop and which as a consequence makes it necessary to leave the sides of the loop open. The present invention overcomes the necessity of an open loop by projecting a portion of the extensible fastening means directly through and beyond the turn in the loop for attachment to its complementary fastening member.

I accomplish the objects of my invention by means of a device, one embodiment of which will be described in the following specification, set forth in the appended claims and is illustratively exemplified in the accompanying drawing, in which Figure 1 is a plan elevational view of the opposite ends of a belt, showing a portion of the loop at one end cut away to disclose the construction of the extensible fastening means; Figure 2 is a substantially longitudinal section view of the belt ends and extensible fastening means engaged with its complementary member, the section being taken along lines 2—2 of Figure 1; and Figure 3 is a perspective view of the slide fastening element.

Referring to the drawing, 10 denotes a leather or fabric strap or belt having one end turned back upon itself for a substantial distance to form a loop 11. The opposite end of the belt 10 is free and carries a slide buckle 12, which consists of an outer plate 13, spaced under plate 14 and pivoted clamp jaw 15 disposed between the two plates and adapted to be forced into engagement with the free end portion of the belt projecting through the space between the plates. The jaw 15 beyond the pivot is provided with a bale 16 which projects outwardly from under the end of the buckle 12, as illustrated in Figures 1 and 2. It is not essential that this particular construction of buckle be used because any unit having a bale or bar may be employed for the purpose.

Disposed partly within the loop 11 is the extensible fastening means, which comprises a rear

17 permanently mounted upon a short strip of leather 18 which is secured by means of stitching 19 to the end of the loop and the overlying portion of the belt. The inner side of the plate 17 is provided with transversely spaced hooks 20, each thereof being connected to an end of a coiled spring 21. The springs 21 are disposed longitudinally of the loop 11 and are connected at their opposite ends to hooks 22 of a slide plate 23. The plate 23 is a substantially U-shaped 10 flat piece of metal having the hooks 22 integral with the closed end of the plate and the arms 24 projecting outwardly in a longitudinal direction through slots 25 in the closed end of the loop 11. The midportion of each arm 24 is slotted longitudinally thereof to form a spring tongue 26 which is turned down slightly at its free end. The free end of each arm 24 is curved upwardly to form a hook 27 overlying the tip of the upturned tongue 26. The purpose of tongues is to 20 allow the bale 16 to pass upwardly into the hooks 27 and when the bale has properly seated itself in the hooks the tongues spring downwardly under the bale and hold it against falling out of the hooks. 25

To adjust the belt 10 to the wearer its free end is threaded through the buckle 12, between the plates 13 and 14 thereof, and over the jaw 15. The hooks 27 are engaged about the bale 16 and the free end of the belt 10 is drawn 30 through the buckle 12 until properly adjusted, the free end overlying the opposite or loop end 11 of the belt and being confined to this position by means of a transverse loop 28 carried by the loop end 11 and admitting the free end of the 35 belt therethrough. Any expansion or contraction of the belt after being adjusted is provided by the extensible fastening means, the arms 24 of which are free to move freely in and out of the slots 25 in the closed end of the loop end 11. 40 The loop end 11 is closed along its opposite sides by rows of stitching 29 so that the fixed plate 17, springs 21 and a portion of the slide plate 23 are entirely encased within the loop.

Having now described my invention and the 45 manner in which the same operates what I claim and desire to secure by Letters Patent is:

1. In a belt or the like, the combination of a strap having one end turned back upon itself and stitched along three sides to form a closed 50 loop and being provided with spaced transverse slots in the turn of the loop, a U-shaped slide plate arranged within the loop and having its arms projecting through the slots and terminating in hooked shaped portions, springs within 55

the loop connected at their forward ends to the closed end of the slide plate and fixed at their opposite ends to the strap, and a buckle adjustable over the free end of the strap and provided with a bale to detachably engage in the hooks of the slide member.

5 2. A belt, as claimed in claim 1, in which the arms of the slide member are provided with spring tongues turned at their free ends to project into the hooks and yield when the bale is

inserted to allow same to pass and then spring outwardly to engage over the bale to hold it in the hooks.

3. A belt, as claimed in claim 1, including a plate fixed on the strap between the strands thereof forming the loop and provided with means to receive and hold the inner fixed ends of the springs.

ARTHUR R. RICHTMYER.
